ABSTRACT OF THE DISCLOSURE

A vibratory compactor in which a roller is connected to the compactor frame by vibration isolator elements at least one of which at each end of the roller resists roller vibrations longitudinally of the frame in tension and compression and vertically in shear. The roller is journaled on a shaft which connects the drum to the frame and which carries eccentric weights which induce the roller vibrations. The shaft is journaled to the frame for rotation about an axis which is eccentric with respect to the axis of rotation of the drum in a direction limiting the amplitude of vibration forced upon the frame by the drum.

BACKGROUND OF THE INVENTION

Field of the invention

The present invention relates to earth compaction equipment and more particularly to a vibratory earth compaction roller.

Description of the prior art

In vibratory compactors of the prior art, elastomer isolator blocks connect the vibratory roller drum to the compactor frame in a manner so as to resist drum vibrations both longitudinally and vertically in shear only, thereby providing maximum freedom of movement of the roller relative to the frame and thus optimum isolation of the frame and drive components from roller vibration. However, it has been found that the use of such an isolator arrangement permits so much longitudinal movement of the drum with respect to the compactor frame, especially with heavy rollers, that isolators fail prematurely. Furthermore, scrapers connected to the compactor frame and used to remove soil from the drum surface become badly damaged when set closely enough to the drum to operate efficiently, and the drum sags excessively when the roller is lowered down a steep embankment.

SUMMARY OF THE INVENTION

The problems as described above with respect to the prior art have been overcome with the compaction roller of the present invention through the provision of isolator means arranged between the roller drum and frame in a manner to resist longitudinal movements of the roller at least partially in tension and compression rather than solely in shear so as to restrict the amplitude of movement between the roller and frame in that direction while still resisting vertical movement of the roller solely in shear for maximum freedom of movement of the roller in its compacting effort. The resulting reduction in the degree of isolation of longitudinal roller movement from the frame is compensated for by an eccentric positioning of the rotational axis of the drum shaft with respect to the rotational axis of the roller drum on such shaft in a manner which limits the amplitude of vibration forced upon the frame.

Accordingly, primary objects of the present invention are to provide:

(1) A vibratory roller with an improved isolator arrangement for increased isolator life;

2

(2) An improved isolator arrangement for a vibratory roller which limits the movement of the drum relative to the frame in the direction of travel to permit proper adjustment of scrapers with respect to the drum while maintaining a clearance between the scrapers and drum, and to resist sag of the drum relative to the frame when operating on steep inclines, without restricting the freedom of movement between the drum and frame in a vertical direction;

(3) A vibratory roller with an isolator arrangement as aforesaid combined with means for reducing the amplitude of vibration forced upon the frame to offset the reduced effective isolation of vibration longitudinally of the frame; and

(4) A vibratory roller with means for varying the eccentricity between the rotational axis of the roller and the rotational axis of the shaft which drives the eccentric weight means to compensate for changes in the amplitude of vibration forced upon the frame by the roller.

BRIEF DESCRIPTION OF THE DRAWINGS

The foregoing and other objects and advantages of the present invention will become more apparent from the following detailed description which proceeds with reference to the accompanying drawing, wherein:

FIG. 1 is a side elevational view of a vibratory compaction roller in accordance with the present invention;

FIG. 2 is a top plan view of the roller of FIG. 1 with a portion of the roller drum broken away for clarity of illustration;

FIG. 3 is a partial sectional view of a modified drum isolator mounting in accordance with the invention;

FIG. 4 is a partial horizontal sectional view showing another modification of drum isolator mounting which is adjustable; and

FIG. 5 is a vertical sectional view taken along the line 5—5 of FIG. 4.

DETAILED DESCRIPTION

With reference to the drawings, FIGS. 1 and 2 show a vibratory compactor 10 including a ground-engaging cylindrical drum roller 12 connected at its opposite ends by a shaft 14 to opposite longitudinal side frame members 16, 17 of a compactor frame 18. Frame 18 is adapted to be towed by a tractor vehicle (not shown) connected to the frame at a hitch 20. A telescoping leg 22 is also provided to support the front end of the frame above the ground surface when disconnected from a tractor as shown.

An internal combustion engine 24 is mounted on the frame forwardly of the roller and transmits rotary power through a drive shaft 26 and gear box 28 to the shaft 14 to rotate the shaft independently of the drum. Shaft 14 mounts eccentric weights 30 and 31 which rotate with the shaft and with centers of gravity offset on the same side of the axis 32 of the main portion of the shaft to serve as a vibration generator means. Roller drum 12 is journaled to the main portion of shaft 14 at internal bearings 34, 35 supported by internal drum webs 37, 38, respectively, to rotate independently of the shaft about axis 32. Thus upon rotation of shaft 32 counterweights 30, 31 transmit vibrations through drum 12 to the surface under compaction.

Opposite ends 40, 41 of drum shaft 14 are journaled in bearings 43, 44 within hub portions 46, 47 of journal support members 49, 50. Each support member includes a pair of longitudinal support arms 52, 53 extending in opposite longitudinal directions from the central hub thereof. The outer ends of the support arms are connected by elastomer isolator members 55, 56 to opposite side frame members 16, 17 to isolate the frame

and supported drive components from vibrations of roller drum 12.

Additional details of general construction of the roller drum and its mounting and isolators are illustrated and described, for example, in the prior copending application of Jack B. Peterson, Ser. No. 642,586, filed May 31, 1967 for Vibratory Compactor. However, in prior art constructions, as shown for example in the aforementioned copending application Ser. No. 642,586, both of the isolators at each end of the drum are connected to the frame in the manner shown with respect to isolator 55, with the isolator extending between and connected to longitudinally extending faces of the frame and support arm so that both vertical and longitudinal vibrations of the drum are resisted by the isolator wholly in shear. Such an arrangement provides for maximum freedom of movement of the drum relative to the frame and thus maximum isolation of the frame, while also providing maximum resistance to movement of the drum in compression and tension transversely of the side frame members.

Contrary to prior constructions, the illustrated compactor has its rear isolator 56 at each end of the drum mounted to an outer support arm portion 58 and a parallel frame portion 59 which extend transversely of the side frame members and parallel to the drum axis so as to resist vibrations of the drum longitudinally of the frame, in tension and compression rather than in shear, while still resisting vertical vibrations in shear only. Isolators 55 and 56 at both ends of the drum are mounted in exactly the same manner.

The effect of the illustrated isolator mounting is to restrict longitudinal movements of the roller relative to the frame while still permitting maximum freedom of vertical movement of the drum relative to the frame as needed for optimum compaction with minimum transfer of vibration to the frame.

With the foregoing isolator arrangement, there would be the possibility that excessive vibration could be transferred to the frame in the longitudinal direction were it not for the provision of means for limiting the amplitude of vibration forced upon the frame by the roller. To this end, the opposite ends 40, 41 of shaft 14 journaled in bearings 43, 44 are offset from the intermediate main portion of the shaft to provide the shaft with an axis of rotation 62 which is eccentric with respect to the axis of rotation 32 of the drum. Shaft axis 62 is offset on the same side of drum axis 32 as are the centers of gravity of eccentric weights 30, 31. Thus upon rotation of shaft 14 the eccentricity of the main body of the shaft and drum on one side of the rotational axis 62 will counteract to some extent the eccentricity of the weights 30, 31 on the opposite side of axis 62 to restrict the amplitude of vibration forced upon journal support members 49, 50 of the frame.

With the amplitude of movement between the roller and the frame effectively limited as aforesaid at least in the longitudinal direction, drum scrapers 64, 65, which are adjustably bolted to the frame for removing soil from the surface of the drum, can be mounted with their blades close enough to the drum surface for effective cleaning without the drum slamming against the blades on uneven ground or on a steep incline. Moreover, isolator life is increased through reduction of the longitudinal amplitude of movement between the roller and frame, and rearward sag of the roller relative to the frame is minimal when the compactor is backed down or towed up a steep embankment.

Although longitudinal movement of the roller in FIG. 2 is limited through placement of the rear isolators to resist such movement solely in tension and compression, this is not necessary so long as at least one isolator element has at least a tensile and compressive component of resistance to vibration in the longitudinal direction. Thus in FIG. 3 a modified drum connection for a drum

12a and shaft 14a with eccentric weight 30a includes an eccentric shaft end 40a journaled in bearing 43a of a modified journal support structure 49a. Journal support 49a has a rearwardly extending support arm 70 with an outer isolator mounting flange 72 extending at an oblique angle with respect to side frame member 16a and the drum axis, and parallel to an oblique isolator mounting flange 74 on side frame member 16a. An isolator member 76 joins support flange 72 and frame flange 74 so as to resist longitudinal vibrations of the drum partly in shear and partly in tension and compression. A second isolator 55a joins a forward support arm 78 of support member 49a to the frame in the usual manner so as to resist longitudinal vibrations wholly in shear. Both of isolators 55a and 76 resist vertical vibrations in shear only like the isolators of FIG. 2.

Referring to FIGS. 4 and 5, a modified drum shaft 14b is provided with an eccentric shaft end 40b which can be adjusted relative to the main body of the shaft to vary the eccentricity of the rotational axis 62a of the shaft relative to the rotational axis 32a of the drum. For this purpose, shaft end 40b is journaled in bearing 43b and includes a flange portion 80 joined by bolts 81, 82 to an abutting flange end 84 of the main body 14b of the shaft. Flange 80 is provided with slots 86, 87 through which bolts 81, 82 extend to permit, when the bolts are loosened, sliding adjustment of shaft end 40b relative to shaft body 14b. Adjustment of the eccentricity of the shaft axis is desirable to compensate for the effect of varying the mass of the drum or eccentric weights or the eccentricity of such weights. The eccentricity of the weights could be varied if desired in a manner, for example, similar to that by which the eccentricity of the shaft is varied.

The drum scrapers of prior compactors would be set quite close to the drum surface on even ground, but upon encountering uneven rocky ground, the scrapers would be damaged by the pounding of the drum against the scrapers. This problem has been eliminated by the isolator arrangement and shaft mounting of the present invention.

Although in the illustrated embodiments, one isolator is arranged with its vertical shear planes at an angle to the vertical shear planes of the other isolator at the same end of the drum, such an arrangement is not absolutely necessary. For example both isolators 55, 56 of FIG. 2 could be arranged with their vertical shear planes extending parallel to the axis of the drum in the orientation of isolator 56. Alternatively, both isolators could be arranged with their vertical shear planes oblique to the axis of the drum in the orientation of isolator 76 in FIG. 3. However, the illustrated arrangements are preferred since the last-mentioned alternatives, and particularly the one mentioned with respect to FIG. 2, could result in excessive axial movement of the roller drum transversely of the frame. Although the shaft ends 40, 41 are illustrated as being enlarged with respect to the main body of shaft 14 for clarity of illustration of their eccentricity, in practice these ends are of reduced diameter relative to the main body of the shaft as shown in the aforementioned prior copending application. Thus in manufacturing the shafts, the eccentricity of the shaft ends can be machined into the shaft.

Having illustrated and described several preferred embodiments of the invention, it should be apparent to those skilled in the art that the same permits of modification in arrangement and detail. I claim as my invention all such modifications as come within the true spirit and scope of the following claims.

I claim:

1. A vibratory compactor including:
a frame having a longitudinal dimension in the direction of travel of said compactor,
a roller having an axis of rotation extending transversely within said frame,

vibrations generating means connected to said roller for vibrating said roller,
an isolator means connecting the opposite ends of said roller to said frame so as to isolate the frame from the vibrations of said roller,
said isolator means resisting vibrations of said roller in a direction normal to said axis of rotation and longitudinally of said frame at least partially in tension and compression,
said isolator means resisting vertical vibrations of said roller in shear in a manner such that vertical vibrations of said roller are resisted to a lesser degree by said isolators than longitudinal vibrations thereof.

2. A vibratory compactor including:

a frame having a longitudinal dimension in the direction of travel of said compactor,
a roller having an axis of rotation extending transversely within said frame,
vibrations generating means connected to said roller for vibrating said roller,
and isolator means connecting the opposite ends of said roller to said frame so as to isolate the frame from the vibrations of said roller,
said isolator means resisting vibrations of said roller in a direction normal to said axis of rotation and longitudinally of said frame at least partially in tension and compression,
said isolator means including a pair of resilient isolator members connecting each end of said roller to said frame,
one of said members being positioned forwardly of the rotational axis of said roller and the other of said members being positioned rearwardly of said axis, at least one of said members connecting said roller to said frame in a manner so as to resist movements of said roller relative to said frame along the path of travel of said roller at least partially in tension and compression.

3. Apparatus according to claim 2 wherein the rearwardly positioned one of said isolator members resists longitudinal movements of said roller relative to said frame in tension and compression.

4. Apparatus according to claim 1 wherein said isolator means includes an isolator element mounted to resist axial movement of said roller partly in shear and partly in tension and compression.

5. Apparatus according to claim 2 wherein one of said pair of isolator members is mounted to resist longitudinal roller vibrations in tension and compression and axial and vertical vibrations in shear, and the other of said isolator members is mounted to resist axial roller vibration in tension and compression and longitudinal vibrations in shear only.

6. Apparatus according to claim 2 wherein one of said pair of isolator members is mounted to resist both longitudinal and axial roller vibrations partly in tension and compression and partly in shear, and the other of said isolator members is mounted to resist axial roller vibrations in tension and compression and longitudinal vibrations in shear only.

7. A vibratory compactor including:

a frame having a longitudinal dimension in the direction of travel of said compactor,
a roller having an axis of rotation extending transversely within said frame,
vibrations generating means connected to said roller for vibrating said roller,
and isolator means connecting the opposite ends of said roller to said frame so as to isolate the frame from the vibrations of said roller,
said isolator means resisting vibrations of said roller in a direction normal to said axis of rotation and longitudinally of said frame at least partially in tension and compression,

said isolator means resisting longitudinal movements of said roller relative to said frame at least partly in tension and compression, vertical movements of said roller relative to said frame in shear, and axial movements of said roller relative to said frame at least partly in tension and compression.

8. A vibratory compactor comprising:

frame means,
a cylindrical drum roller within said frame means,
shaft means extending axially within said roller,
journal means journaling said shaft means to said frame means,
bearing means journaling said roller on said shaft means,
eccentric weight means on said shaft means having a center of gravity offset from the rotational axis of said roller and driven by said shaft means,
power means on said frame means for rotating said shaft means independently of said roller so as to induce vibrations in said roller in directions normal to the axis of rotation of said roller,
said journal means including journal support means and isolator means connecting said support means to said frame means in a manner providing resistance at least partially in tension and compression to vibrations of said roller longitudinally in the direction of travel of said compactor,
said isolator means including resilient means resisting roller vibrations vertically in shear only and longitudinally partly in shear and partly in tension and compression in a manner such that said resilient means offers a greater resistance to longitudinal vibrations of said roller than to vertical vibrations thereof.

9. A vibratory compactor including:

a frame having a longitudinal dimension in the direction of travel of said compactor,
a roller having an axis of rotation extending transversely within said frame,
vibrations generating means connected to said roller for vibrating said roller,
and isolator means connecting the opposite ends of said roller to said frame so as to isolate the frame from the vibrations of said roller,
said isolator means resisting vibrations of said roller in a direction normal to said axis of rotation and longitudinally of said frame at least partially in tension and compression,
said isolator means including at least two elastomer isolator members at each end of said shaft means, one resisting longitudinal vibrations of said roller in shear and the other resisting longitudinal vibrations of said roller at least partly in tension and compression.

10. A vibratory compactor including:

a frame having a longitudinal dimension in the direction of travel of said compactor,
a roller having an axis of rotation extending transversely within said frame,
vibrations generating means connected to said roller for vibrating said roller,
and isolator means connecting the opposite ends of said roller to said frame so as to isolate the frame from the vibrations of said roller,
said isolator means resisting vibrations of said roller in a direction normal to said axis of rotation and longitudinally of said frame at least partially in tension and compression,
said isolator means including at least two elastomer isolator members at each end of said shaft means, one resisting longitudinal vibrations of said roller in shear only, the other resisting longitudinal vibrations of said roller in tension and compression only, and both of said isolator members resisting vertical vibrations of said roller in shear only.

11. A vibratory compactor comprising:
 frame means,
 a cylindrical drum roller within said frame means,
 shaft means extending axially within said roller,
 journal means journaling said shaft means to said frame
 means,
 bearing means journaling said roller on said shaft
 means,
 eccentric weight means on said shaft means having a
 center of gravity offset from the rotational axis of
 said roller and driven by said shaft means,
 power means on said frame means for rotating said
 shaft means independently of said roller so as to
 induce vibrations in said roller in directions normal
 to the axis of rotation of said roller,
 said journal means including journal support means
 and isolator means connecting said support means to
 said frame means in a manner providing resistance
 at least partially in tension and compression to vi-
 brations of said roller longitudinally in the direction
 of travel of said compactor,
 said shaft means having an axis of rotation offset from
 and parallel to the axis of rotation of said roller in
 a direction tending to limit the amplitude of vibra-
 tion transmitted from said shaft means to said jour-
 nal means.
12. Apparatus according to claim 11 including means
 connected to said shaft means for changing the degree of
 eccentricity of the rotational axis of said shaft means with
 respect to the rotational axis of said roller.
13. A vibratory compactor comprising:
 frame means,
 a cylindrical drum roller within said frame means,
 shaft means extending axially within said roller,
 journal means journaling said shaft means to said
 frame means,
 bearing means journaling said roller on said shaft
 means,
 eccentric weight means on said shaft means having a
 center of gravity offset from the rotational axis of
 said roller and driven by said shaft means,
 power means on said frame means for rotating said
 shaft means independently of said roller so as to
 induce vibrations in said roller in directions normal
 to the axis of rotation of said roller,
 said journal means including journal support means
 and isolator means connecting said support means to
 said frame means in a manner providing resistance
 at least partially in tension and compression to vi-
 brations of said roller longitudinally in the direction
 of travel of said compactor,
 said journal means mounting said shaft means for ro-
 tation about an axis which is eccentric with respect to
 the axis of rotation of said roller,
 the rotational axis of said shaft means and the center
 of gravity of said eccentric weight means being off-
 set on the same side of the rotational axis of said
 roller.
14. A vibratory compactor comprising:
 frame means,
 a cylindrical drum roller within said frame means,
 shaft means extending axially within said roller,
 journal means journaling said shaft means to said frame
 means,

bearing means journaling said roller on said shaft
 means,
 eccentric weight means on said shaft means having a
 center of gravity offset from the rotational axis of
 said roller and driven by said shaft means,
 power means on said frame means for rotating said
 shaft means independently of said roller so as to in-
 duce vibrations in said roller in directions normal to
 the axis of rotation of said roller,
 said journal means including journal support means
 and isolator means connecting said support means to
 said frame means in a manner providing resistance
 at least partially in tension and compression to vi-
 brations of said roller longitudinally in the direction
 of travel of said compactor,
 said frame means including a pair of laterally opposed
 side frame members,
 said roller being positioned between said side frame
 members,
 said journal means including a hub portion containing
 a bearing for said shaft means, a pair of support
 arms extending longitudinally in opposite directions
 forwardly and rearwardly from said hub portion, an
 elastomer isolator member connecting a vertical face
 of one of said support arms to a parallel face of the
 adjacent said side frame member, with said faces
 extending normal to the rotational axis of said roller
 so that said isolator member resists longitudinal
 vibrations of said roller in shear,
 a second elastomer isolator member connecting a ver-
 tical face of the other of said support arms to a
 parallel face of the adjacent said side frame mem-
 ber, with said last-mentioned faces extending at an
 angle with respect to said first-mentioned faces so
 that said second isolator member resists longitudinal
 movement of said roller relative to said side frame
 members at least partially in tension and compres-
 sion.

15. A vibratory compactor comprising:
 a frame means,
 a drum roller within said frame means,
 shaft means journaled to said frame means for ro-
 tation about a first axis and connecting said roller to
 said frame means,
 bearing means journaling said roller to said shaft means
 for rotation about a second axis parallel to and off-
 set from said first axis,
 and means connecting to said shaft means for varying
 the offset of said second axis from said first axis.

16. A vibratory compactor according to claim 15
 wherein said shaft means drives eccentric weight means
 rotatable with said shaft means about said first axis, the
 center of gravity of said eccentric weight means and said
 first axis being offset on the same side of said second axis.
